UNITED STATES PATENT OFFICE.

OTTO F. FOGELSTRAND, OF KENSINGTON, CONNECTICUT, ASSIGNOR TO
HART MANUFACTURING COMPANY, OF SAME PLACE.

DESIGN FOR SASH-FASTENER.

Specification forming part of Design No. 5,696, dated March 19, 1872.

To all whom it may concern:

Be it known that I, OTTO F. FOGELSTRAND, of Kensington, in the county of Hartford and State of Connecticut, have invented and produced a new and original Design for a Sash-Fastener, of which the following is a specification:

The nature of my design is fully represented by the accompany engraving, to which reference is made.

A represents the body of the lock proper; B, the fastening-lever; and C, the catch-plate.

The sides of the lever B, top and front of the body A, are bordered by a raised ledge, inside of which are raised figures of stars, groups of leaflets, and X's, as shown. The sunken surface of the various parts is covered with small triangular figures.

I claim as my invention—

The design for a sash-fastener, as shown.
OTTO F. FOGELSTRAND.
